UNITED STATES PATENT OFFICE

ROBERT J. COPELAND, OF TORONTO, ONTARIO, CANADA

ATTACHMENT FOR LOOSE-LEAF BINDERS

Application filed October 1, 1927. Serial No. 223,435.

The principal objects of this invention are to facilitate the handling of the accounting sheets in a loose leaf binder by providing a simple and effective means for shifting the relative position of one or more sheets in relation to the remainder in the binder and to provide a device which may be operated on any type of prong binder.

A further important object is to materially reduce the cost of accounting binder equipment and to enable the utilization of fixed prong binders as shift binders.

The principal feature of the invention consists in providing a supplementary set of prongs adapted to be temporarily mounted on the permanent prongs of the binder in sliding relation thereto to effect the shifting of the accounting sheets.

In the accompanying drawings, Figure 1 is a perspective view of a binder shown open and illustrating the application of my attachment to one set of the prongs.

Figure 2 is a view similar to Figure 1 showing the attachment shifted.

Figure 3 is an enlarged perspective view of a portion of my improved attachment shown mounted on the binder prongs.

Figure 4 is an end elevation showing a portion of a binder with my attachment housed therein.

Figure 5 is a detail plan view of the attachment.

In the handling of accounting sheets in loose leaf binders it is frequently found necessary to shift groups of accounting sheets in relation to other groups in order to insert extra sheets or in rearranging the sheets upon the removal of any sheets. This result has been achieved in a crude manner by the use of transfer forks consisting of a bar having a plurality of short prongs thereon which is placed by hand into the prong holes of the sheets so that the sheets may be lifted out of the binder and transferred to a different position. Other means have been devised in the form of hinged members forming a permanent part of the binder back which may be shifted longitudinally by sliding on a hinge pin.

This invention consists in providing a

prong device to be placed upon the permanent prongs of the binder and so constructed and arranged as to be capable of being shifted longitudinally in the binder back without removal by sliding on the permanent prongs to effect the necessary shifting in position of the sheets.

In the form of the invention herein shown a strip 1 of sheet metal is bent transversely to conform to the arch of the curvature of the binder prongs 2 and one edge of the strip is bent back to form a lip 3 so that a pocket is formed between the main portion of the strip 1 and the lip 3. This pocket 4 is adapted to receive the pointed ends of one set of the prongs of the binder and it is capable of sliding in a longitudinal direction on the set of prongs. The edge of the pocket 4 formed by the turned-back lip 3 of the metal strip is perforated at regular intervals in its length which intervals correspond with the spacing of the prongs of the binder and short curved prongs 5 are inserted into the perforations and rigidly secured in place to project outwardly from the set of prongs on which the strip is placed.

A block 6 is secured within the pocket formed in the metal strip in such a position that one end thereof will engage one of the permanent prongs 2 when the short prongs 5 register with one set of holes in the sheets 7 and the distance between the other end of this block and the next adjacent permanent prong 2 is equal to the distance between the perforations in the sheets so that when the attachment is moved longitudinally on the ends of the permanent prongs, the other end of the block will engage the next adjacent prong to bring the supplementary prongs into proper alignment with another set of holes in the sheets.

It must be seen that in placing this attachment on a set of prongs of a binder the supplementary prongs carried thereby will, when the block 6 is moved to abut one of the permanent prongs, engage or register with one set of holes and as the supplementary prongs are formed to conform with the curvature of the other prong in the adjacent set, the sheets to be transferred or shifted

will slip on to the temporary prongs. Then by moving the metal strip longitudinally the sheets are carried with the temporary prongs to the other position and the sheets may then be slipped back to the permanent prongs.

It will be noted that when my device is placed on one set of prongs the ends of the other set of permanent prongs may be swung close up to the rounded edge of the lip 3, consequently the supplementary prongs 5 will overlap these ends and there will be no danger of any sheet becoming misplaced and as the prongs are all rounded on the ends, when a sheet or group of sheets have been moved on to the supplementary prongs, the shift device may be moved without the necessity of spreading the binder prongs farther apart as they will, on the movement of the shift device, readily slip under the rounded points.

If it is desired to move a sheet or sheets from the binder when this attachment is in place, it is merely necessary to open the binder back in the usual manner and the points of the supplementary prongs will be carried clear of the ends of the permanent prongs of which the sheets are desired to be removed.

I have shown herein a means for holding my shift attachment housed in the binder back between the curved prongs 2 and the hinge, but the attachment is however readily detachable. In the structure shown, I provide small metal clips 8 which fit over the end edges of the binder back and these clips are provided with small hooks 9 over which the loop ends of an elastic 10 are hooked. The other ends of the elastic loop are secured to prongs 11 which are formed in the sheet-metal strip.

I have shown my device formed of a strip of sheet metal, but it will be readily understood that the sliding member which is adapted to be inserted on to the ends of the permanent prongs of the binder, may be readily formed of cast metal having the temporary prongs 5 cast therein, and it will be also understood that I may without departing from the essential features of this invention, use other means for holding the device temporarily in the book, or the device may be used without such holding means and be transferred from book to book as it may be required.

It will be readily seen that the device is extremely simple and will be very cheap to manufacture.

What I claim as my invention is:—

1. An attachment for loose-leaf binders, having sets of binder prongs, comprising a member having a plurality of supplementary prongs, said member being adapted to slidably engage the ends of one set of permanent prongs of the binder, clips adapted to be secured to the binder back, and elastic means

secured to said slidable member and connected to said clips.

2. An attachment for loose-leaf binders having curved binder prongs, comprising a strip of metal folded longitudinally and adapted to fit over the ends of said binder prongs and to slide thereon, and supplementary prongs secured to said folded member and extending therefrom.

3. An attachment for loose-leaf binders having curved binder prongs, comprising a strip of metal folded longitudinally and adapted to fit over the ends of said binder prongs and to slide thereon, and supplementary prongs secured to the closed edge of said folded member and extending beyond the binder prongs on which the device is mounted.

4. An attachment for loose-leaf binders having curved binder prongs, comprising a strip of metal folded longitudinally and adapted to fit over the ends of said binder prongs and to slide thereon, said folded member having a plurality of openings formed in the closed edge thereof, and supplementary prongs confined between the side walls of said folded member and extending through said openings and forming rigid prong extensions.

5. An attachment for loose-leaf binders having curved binder prongs, comprising a strip of metal folded longitudinally and adapted to fit over the ends of said binder prongs and to slide thereon, supplementary prongs secured to said folded member and extending therefrom, and means for limiting the longitudinal movement of said folded member on the binder prongs.

6. An attachment for loose-leaf binders having curved binder prongs, comprising a strip of metal folded longitudinally and adapted to fit over the ends of said binder prongs and to slide thereon, supplementary prongs secured to said folded member and extending therefrom, and stop means interposed between the doubled walls of the folded member adapted to engage the binder prongs to limit the longitudinal movement of said member.

7. An attachment for loose-leaf binders having curved binder prongs, comprising a strip of metal folded longitudinally and adapted to fit over the ends of said binder prongs and to slide thereon, said member having its doubled walls curved to conform to the longitudinal curvature of the binder prongs and spaced apart a distance substantially equal to the thickness thereof, and curved supplementary prongs secured between the curved spaced walls of said member and extending beyond the closed edge thereof.

8. An attachment for loose-leaf binders having curved binder prongs, comprising a strip of metal folded longitudinally and adapted to fit over the ends of said binder prongs and to slide thereon, and a plurality

of supplementary prongs confined between the side walls of said member in overlapped relation to the prongs on which the device is mounted, said supplementary prongs extending beyond the closed edge thereof.

5. 9. An attachment for loose-leaf binders having curved binder prongs, comprising a strip of metal folded longitudinally and adapted to fit over the ends of said binder prongs and to slide thereon, supplementary prongs secured to said folded member and extending therefrom, and a stop flange extending transversely between the side walls of said folded member and of a lesser length than the distance between two adjacent prongs of the binder adapted to engage and limit the longitudinal movement of the folded member on the binder prongs.
